UNITED STATES PATENT OFFICE.

WILLIAM E. FLETCHER, OF TAMAQUA, PENNSYLVANIA, ASSIGNOR TO ATLAS POWDER COMPANY, OF WILMINGTON, DELAWARE, A CORPORATION OF DELAWARE.

RETORT-FURNACE.

1,156,595.

Specification of Letters Patent. Patented Oct. 12, 1915.

Application filed January 3, 1914. Serial No. 810,236.

To all whom it may concern:

Be it known that I, WILLIAM E. FLETCHER, a citizen of the United States, residing at Tamaqua, in the county of Schuylkill and State of Pennsylvania, have invented certain new and useful Improvements in Retort-Furnaces, of which the following is a specification.

The object of the invention is to provide a retort furnace, especially adapted for use in the distillation of nitric acid, wherein there is effected an economy in the consumption of fuel, and consequently in the application of heat to the retort such a distribution of heat units to the walls of the retort as to insure a uniform heating thereof, to secure the necessary reaction, while avoiding both the overheating of those portions of the retort above the level of, and not protected by, the liquid, to produce decomposition, or the local cooling of such portions of the retort to produce condensation and hence reaction of the acid on the metal, and thereby to effect a maximum yield of the product, with due regard to simplicity and economy of construction in the furnace and retort mounting. These objects are attained in the preferred embodiment of the invention by the approximate relative proportions of the retort and furnace; by the disposition of the grate or source of heat supply relative to the retort and the draft outlet to the stack; by the direction of the draft or circulation through the furnace relative to the retort; by the provision of means for securing the expansion of the gases and retardation of the current or flow of the products of combustion; by supporting the retort out of contact with the masonry walls of the furnace, but sufficiently close to the same to form therewith a "blind" passage or compartment, so that the vaporous contents of the furnace are heated by convection or conduction; by the contraction or reduction of the cross sectional area of the passage between the retort and the walls of the furnace toward the top thereof; by removing the products of combustion from the source of heat supply in a direction substantially parallel to the outside surface of the retort and in a direction away from the upper portion of the retort, whereby there is produced a relative and graduated attenuation or rarefaction of the gases or vapors

toward the upper portion of the retort, and 55 by constructing the retort in such a manner as to allow for the unavoidable relative expansion of its parts and provide for economical replacement of the portion thereof which is subjected to the maximum effects of the 60 heat necessary for distillation.

It will be understood that while a preferred embodiment of the invention is disclosed in the accompanying drawings, various changes in the form, proportions and 65 minor details of construction may be resorted to without departing from the spirit of the invention.

In said drawings.—Figure 1 represents a cross sectional view of the retort furnace 70 showing the retort in elevation, and Fig. 2 represents a longitudinal sectional view of the furnace and retort, and illustrating the normal course of the products of combustion from the source of heat supply to the 75 outlet leading to a stack (not shown).

In the construction illustrated, the retort 10 is arranged in the upper portion of the furnace, which may be constructed of brick, concrete or other appropriate masonry, and 80 in what may be termed for convenience, an offset or pocket, with reference to the course of the products of combustion from the grate or source of heat supply 11 to the outlet 12, which latter may lead to any suitable 85 stack or draft-inducing means, while between the source of heat supply and the outlet 12 is arranged an enlarged expansion chamber 13 to effect an expansion and retardation of the products of combustion in 90 the passage thereof from said source of heat to the outlet. This arrangement insures a movement of the products of combustion from the source of heat supply along the under surface of the retort to the outlet of 95 the furnace, and the direct application of the heat of the products of combustion solely to the bottom of the retort, whereby the deterioration of the retort is confined mainly to the bottom thereof. The retort 100 shown is made sectional with the bottom section 10^a separable from the upper portion 10^b to provide for the renewal of the former, when required, without necessitating the renewal of the entire retort, and also to provide for a certain compensation due to any unavoidable inequality of expansion of the material constituting the retort. The bot-

tom section of the retort is entirely unsupported, otherwise than by the upper portion thereof, and the support of the retort in the furnace is entirely independent of the masonry walls of the furnace, being secured in the construction illustrated by means of metallic girders or I-beams 14, upon which bear the brackets 15 on the upper section of the retort, the material selected for the girders 10 preferably having a coefficient of expansion approximately corresponding with that of the walls of the retort, so that the heating thereof will correspond approximately with that of the walls of the retort, or, if there is 15 any difference, will be more rapid than that of the walls of the retort, to avoid the disadvantages incident to "chilled spots" or cooler zones on the walls of the retort, which, in the ordinary operation of such devices, produce condensation of nitric acid 20 and consequently destructive reaction on the metal walls of the retort.

The sections 10 and 10^a may be detachably secured together in any convenient way; 25 as by providing their meeting edges with flanges, and using clamps to hold the flanges in contact; or by employing bolts and nuts for the same purpose, after first boring as many holes as may be needed in the flanges. 30 The usual outlets and means for charging and giving access to the interior of the retort are shown at 16, 17 and 18, respectively, the connection of the casings of these outlets with the retort being indirect, to avoid 35 affecting the expansion of the walls of the retort or the conduction of heat therefrom or thereto.

The chamber or pocket of the furnace in which the retort is arranged is of a size proportionate to the dimensions of the retort, 40 such as to provide a comparatively restricted passage around the sides, ends and top of the retort, whereby the heating of those portions of the retort is effected by convection, the draft from the source of heat supply 45 to the outlet of the furnace being in a direction away from said passage, and serving, in a degree, to attenuate or rarefy the gases, and to a certain extent to neutralize 50 the tendency of the heated gases to rise to the top of the furnace, and thereby overheat those portions of the retort which are above the level of the liquid contents of the retort, and which therefore are not protected by 55 said liquid contents. The effect of this arrangement is to insure a comparatively uniform heating of the retort walls to prevent the destructive and expensive consequences

of decomposition and condensation of the product.

What is claimed is:

1. A retort furnace wherein the course of the products of combustion from the source of heat supply to the outlet is in a direction substantially parallel to the bottom of the 65 retort, and having a pocket enveloping the retort between said source of heat supply and the outlet.

2. A retort furnace wherein the course of the products of combustion from the source 70 of heat supply to the outlet is downward, and wherein the retort is located above the source of heat supply.

3. A retort furnace having its source of heat supply and its outlet at opposite sides 75 of the furnace and having the retort in a pocket above and out of the course of the products of combustion from the source of heat supply to the outlet, and separated from the walls of the furnace to form a 80 "blind" passage.

4. A retort furnace having its source of heat supply and its outlet at opposite sides of the furnace and having the retort in a pocket above and out of the course of the 85 products of combustion from the source of heat supply to the outlet, and separated from the walls of the furnace to form a "blind" passage, an enlarged expansion chamber being provided beneath the retort 90 and between the source of heat supply and the outlet.

5. A retort furnace having the retort located in a pocket out of the course of the products of combustion from the source of 95 heat supply to the outlet and separated from the walls of the furnace to form a "blind" passage in communication with the space connecting the source of heat supply with said outlet.

6. A retort having a separable bottom section, and supporting devices engaged and in contact with the upper section thereof.

7. A retort furnace having supporting girders, a retort having a body portion with 105 projections resting on said girders, and a detachable bottom portion secured to the body portion below the girders, and means connected with the retort for giving access to both of said portions.

In testimony whereof I affix my signature in presence of two witnesses.

WILLIAM E. FLETCHER.
